UNITED STATES PATENT OFFICE

102,310

DESIGN FOR A VACUUM CLEANER CASING

Walter C. Reed, North Hollywood, Calif.

Application September 30, 1936, Serial No. 65,070

Term of patent 14 years

To all whom it may concern:

Be it known that I, Walter C. Reed, a citizen of the United States, residing at North Hollywood, in the county of Los Angeles and State of California, have invented a new, original, and ornamental Design for a Vacuum Cleaner Casing, of which the following is a specification, reference being had to the accompanying drawing, forming part thereof.

Fig. 1 is a side elevation,

Fig. 2 is a front elevation of a vacuum cleaner casing showing my new design.

A fragmentary showing in dotted lines is made in the drawing to indicate the air hose attached to the casing of the vacuum cleaner.

I claim:

The ornamental design for a vacuum cleaner casing as shown and described.

WALTER C. REED,
